UNITED STATES PATENT OFFICE.

WILLIAM FRANKLIN COLE, OF WACO, TEXAS.

SURGICAL INSTRUMENT.

Application filed September 8, 1921. Serial No. 499,139.

My invention is an improvement in surgical instruments, and has for its object to provide an instrument of the character specified by means of which enemas may be given 5 in a sitting position, and without the necessity for the patient assuming a reclining position.

In the drawings:—

Figure 1 is a perspective view of the improved instrument.

Figure 2 is a side view with parts in section.

In the present embodiment of the invention, a curved tube 1 is provided having at 15 one end a ball shaped head 2, and having at the other a lateral tubular extension 3. The bore 4 of the tube is continuous with the bore 5 of the extension, and the said bores communicate on a curve as clearly shown in 20 Figure 2, so that no impediment is offered to the passage of the liquid.

At the free end of the tubular extension 3 there is provided a ball shaped head 6, and it will be noticed by referring to Figure 2 25 that the bore 5 is choked at the head 6. The extension 3 is toward the concave face of the tube, and at the connection between the extension and the tube the tube is enlarged in a ball-shape as shown at 7.

30 The extension 3 may be integral with the tube as shown, or it may be detachably connected therewith as may be desired.

In use, a hose 8 as shown in Figure 1, may be connected with the head 2, by slipping 35 the end of the hose over the head, and this hose may lead from any suitable source of supply. While the extension 3 has an olive-shaped tip, it is obvious that any desired tip might be used.

40 In operation, the improved instrument may be inserted without the necessity for the person upon whom it is used to recline, and while such person is in sitting position. Neither is it necessary to pass the hand down 45 beneath the closet seat, since the stem 1 is rigid and serves as a handle for handling the tip. It will be observed that the tube 1 is curved for the greater part of its length from its juncture with the tubular extension 50 3 to lie substantially along the arc of a

circle extending through approximately 90° and that the tubular extension 3 extends on the concavely curved side of the arcuately curved portion of said tube substantially at right angles with said tube. The tube 1 is 55 curved for the remainder of its length reversely to the curvature of the first named portion thereof, whereby the last named or free end portion of the tube may serve as a handle and is thus adapted to be grasped 60 and manipulated by the user when the latter is in sitting position to permit the convenient and effective use of the device without there being any necessity of the user passing the hand grasping the tube beneath the closet 65 seat.

Since the portion of the tube 1 on which the tubular extension 3 is formed curves along an arc of approximately 90° and the tubular extension 3 extends substantially at 70 right angles to the tube at the inner side of the arc, it will be manifest that an upward pull on the tube will cause axial movement of the tubular extension in an upward direction also. The tubular extension 3 therefore 75 can be conveniently and easily moved to and from applied position by the user of the device while he is in a sitting position.

I claim:

As an article of manufacture, an instrument of the character described comprising a tube having a portion thereof curved substantially along the arc of a circle extending through approximately 90° and having a straight tubular extension at one end of the 85 arcuately curved portion, the bores of the straight tubular extension and the arcuately curved portion being continuous one with the other and the straight tubular extension extending on the concavely curved side of the arcuately curved portion of said tube substantially at right angles with said tube, the latter also including a portion at the other end of the arc curved reversely to the first named arc, said tube being enlarged externally at the juncture of said straight tubular extension and said arcuately curved portion, to have substantially the shape of a 95 sphere.

WILLIAM FRANKLIN COLE.
